PORTABLE FLUID MIXER

George G. Stevenson, Los Angeles, Calif., assignor to Semco Research, Inc., Inglewood, Calif., a corporation of California

Filed May 22, 1959, Ser. No. 815,001

22 Claims. (Cl. 259—37)

This invention relates to an apparatus for mixing fluid materials such as fluid materials including a catalyst to produce a highly viscose sealant composition of the general character of a synthetic rubber-like sealant known to the trade as Thiokol. An apparatus of this type is disclosed in the Trumbull et al. Patent No. 2,859,017, which disclosure is hereby incorporated in the present disclosure by reference.

In a typical use for such a composition, the sealant mixture is placed in dispensing tubes having suitable dispensing nozzles by means of which the sealant is applied where required. Once such a mixture is compounded with the included catalyst, it must be used within a few hours. For this reason, the sealant is mixed in small batches only as required.

The invention is particularly directed to the problems involved in providing such an apparatus in the form of a portable unit that may be used on construction jobs. The invention thus meets a need for a compact light-weight unit which may be used in a time-saving manner to mix sealant for application to a building structure, for example, to form seals around metal window frames.

One of the problems involved is to keep the weight of the apparatus low. This problem is met by a light-weight upright structure which consists essentially of a light-weight horizontal base and a hollow upright column fixedly mounted on the base structure. Such a support structure with all the working parts mounted thereon may be easily lifted from a truck by one man and placed on the ground or on any available surface ready for operation.

A feature of the invention is the manner in which it provides for mixing the ingredients in the original container in which the ingredients are sold. The unit provides a can opener to remove the top of the usual cylindrical metal container and the unit provides a closure which is slidably mounted inside the container to replace the removed top. The unit further provides a dasher inside the container beneath the closure for reciprocation to mix the ingredients with the required efficiency.

One of the problems to which the invention is directed is to cause the closure to confine the ingredients in the container in an airtight manner and to permit power to be transmitted through the closure to actuate the dasher for cyclic movement between the closure and the bottom of the container. For this purpose, the invention provides spring means to urge the closure downward against the confined ingredients with the required force and further positions the dasher on the lower end of a shaft that extends slidably through the closure.

A motor for driving the shaft is mounted on the upright column in a vertically movable manner and the motor driven shaft is formed with a screw thread that is engaged by a fixed threaded collar. Thus the rotation of the shaft by the motor causes the shaft to shift axially by screw action, the motor shifting with the shaft. The dasher at the lower end of the shaft moves axially with the shaft and simultaneously rotates with the shaft. The motor is reversible and means is provided to reverse the motor automatically in response to approach of the dasher to the bottom of the container and again in response to approach of the dasher to the closure.

Another problem to which the invention is directed is to provide a simple and convenient arrangement for dis-

2

pensing the completely mixed ingredients. For this purpose, the closure is provided with a dispensing port or nozzle for filling dispensing tubes and provision is made for operatively connecting the closure to the vertical shaft in such manner that the closure may be driven downward by the motor to dispense the mixed materials. In accord with this concept, a control arrangement is provided which permits the motor either to operate automatically for the mixing operation or to operate under close manual control for the dispensing operation.

10 The motor may be either an electric motor or an air motor. In many instances where compressed air is available on a construction job, it is more convenient to use compressed air for the motive force instead of electricity. In this regard, a feature of the invention is the provision of pneumatic controls for a pneumatic motor which permits the pneumatic motor, like the electric motor, to be either reciprocated automatically for the mixing operation or to be manually controlled for actuating the closure in the dispensing operation.

20 The various features and advantages of the invention may be understood by reference to the following detailed description and the accompanying drawings.

In the drawings, which are to be regarded as merely illustrative:

25 FIG. 1 is a side elevation with parts broken away showing the presently preferred embodiment of the invention which incorporates an electric motor;

FIG. 1a is a somewhat enlarged fragmentary view, partly in side elevation and partly in section, showing how a split thrust collar may be mounted on the vertical shaft to force the closure member downward;

FIG. 2 is a sectional view taken as indicated by the line 2—2 of FIG. 1;

30 FIG. 3 is a side elevation of the same apparatus as seen along the line 3—3 of FIG. 1;

FIG. 4 is a fragmentary view partly in side elevation and partly in section illustrating the dispensing operation;

40 FIG. 5 is an enlarged bottom plan view of the dasher;

FIG. 6 is a wiring diagram of the control system;

FIG. 7 is a diagram of an air motor and an associated control system;

FIG. 8 is a diagram of the valve arrangement in the valve block in FIG. 7;

FIG. 9 is a sectional view showing the construction of one of the valves in the valve block; and

FIG. 10 is a view partly in side elevation and partly in section showing how the reversing valve unit of FIG. 7 may be constructed.

General Arrangement

The essential parts of the first embodiment of the invention shown in FIGS. 1 to 5 include: an upright support structure comprising a base 20 and a hollow column 22 of rectangular cross section; a jacket 24 to removably embrace and reinforce an open-topped container 25 on the base 20; a closure member 26 with a circumferential O-ring 27 to fit slidably in the container 25 against the ingredients therein; a slide member 28 that is slidably mounted on the rectangular column 22 and carries the closure member 26; a coil spring 29 inside the hollow column 22 to urge the slide member 28 downward thereby to urge the closure member 26 downwardly against the ingredients in the container 25; a pivoted latch arm 30 to releasably engage the slide member 28 to hold the closure member 26 elevated in opposition to the coil spring 29 for cleaning operations; a dispensing nozzle 31 in the closure member 26 which nozzle may be closed when desired by an elongated plug 32; an electric motor 34 that is slidably mounted on the hollow column 22 for vertical movement; a motor shaft 35 extending downward from

the motor through the closure member 26, which shaft has a screw thread 36 above the closure member; a fixed sleeve 38 that is supported by the column 22 and is internally threaded for engagement with the screw thread 36 of the motor shaft to cause the shaft and the motor to move vertically by screw action in response to rotation of the shaft; a split thrust collar 39 (FIG. 1a) that may be removably mounted on the motor shaft 35 for abutment against the closure member 26; a dasher 40 with a circumferential series of elongated apertures 41 (FIG. 5), the dasher being fixedly mounted on the lower end of the shaft 35 below the closure member 26 to be rotated by the shaft and to be simultaneously reciprocated between the bottom of the container and the closure member for the purpose of intermixing the ingredients in the container; a reversing switch 42 movable with the motor 34 for reversing the motor; an upper stop 44 connected with the closure member 26 for contacting the reversing switch 42 to reverse the motor when the dasher approaches the closure member; a second fixed lower stop 45 to contact the reversing switch for reversing the motor when the dasher approaches the bottom of the container 25; a manually operable master switch 46 to start and stop the motor 34; a manually operable three-position switch 48 having an "up" position, a "stop" position and a "down" position for manual control of the motor 34; and a selector switch 50 movable to one position to place the motor under the control of the reversing switch 42 and movable to an alternate position to place the motor under the control of the manual switch 48.

This embodiment of the invention further includes a can opener 52 for the convenience of the operator, the can opener being mounted on the rectangular column 22 by means of a bracket arm 54. This can opener may be of conventional construction.

Operation

The sealant material is supplied in the closed container with the necessary catalyst in a separate receptacle. The can opener 52 is employed to remove the top of the container in a smooth manner and the catalyst is then introduced into the sealant material in the container. With the motor shaft 35 at an upper position and the dasher 40 on the lower end of the shaft holding the closure member 26 at an elevated position, the open-top container 25 is placed on the base 20 and enclosed by the jacket 24. The split thrust collar 39 is then placed on the motor shaft 35 above the closure member 26 thereby operatively connecting the closure member to the motor shaft for downward movement therewith. The three-position manual switch 48 is placed in its neutral position; the selector switch 50 is positioned for manual operation; and the master switch 46 is closed in preparation for manual operation.

The three-position manual switch 48 is then manipulated to cause the motor shaft 35 to move downward by screw action with the thrust collar 39 abutting the closure member 26 to force the closure member downward into the open-topped container 25. The dasher 40 is close to the underside of the closure member 26 when the thrust collar 39 is used. The three-position manual switch 48 is "jogged" during this operation, i.e., repeatedly shifted between its "stop" and "down" positions to lower the closure member 26 cautiously and to give opportunity for the open-top container to be maneuvered into an accurately centered position for receiving the closure member. Cautious downward movement of the closure member 26 is continued to lower the closure member against the material in the open-top container and to give the free air on top of the material a chance to escape through the nozzle 31. When the material starts to flow out of the nozzle, the plug 32 is screwed into the nozzle.

The split thrust collar 39 is then removed from the motor shaft 35 and the selector switch 50 is positioned to place the motor under control of the reversing switch 42

for automatic operation. The motor rotates the shaft 35 to reciprocate the dasher 40 with the reversing switch operated by the upper stop 44 when the dasher approaches the closure 26 and with the reversing switch operated by the lower stop 45 when the dasher approaches the bottom of the container 25. Each downward movement of the shaft 35 displaces material in the container to cause corresponding upward movement of the closure member 26 against the resistance of the spring 29.

The dasher 40 is highly effective because the central area, i.e., the area of the inner half of the radial dimension, is blank so that material in the path of the dasher is displaced radially outward to the dasher slots 41. With the dasher rotating as well as reciprocating, the inclined slots 41 are especially effective for intermixing the ingredients.

When the dasher 40 has been reciprocated through the number of cycles for complete and homogeneous intermixture of the ingredients in the container 25, the motor is stopped either by means of the master switch 46 or by placing the three-position manual switch 48 in its "stop" position. The selector switch 50 is then moved to the position for manual operation. With the selector switch 50 positioned for manual operation, with the three-position manual switch 48 at its "stop" position, and with the master switch 46 closed, the three-position switch 48 is "jogged" upward to shift the motor shaft 35 upward cautiously to a position with the dasher 40 close to the closure member 26 to permit the thrust collar 39 to be again installed on the motor shaft 35. The plug 32 is then removed to open the nozzle 31 so that cartridges may be filled for use in applying the sealant for its purpose.

FIG. 4 shows how a cartridge 55 may be positioned by hand against the nozzle 31 for a filling operation. To fill the cartridge, the three-position manual switch 48 is "jogged" downward for cautious downward movement of the closure member 26 to force the mixed material out of the container through the nozzle 31 into the cartridge. When the cartridge is full, the three-position manual switch 48 is "jogged" upward slightly to relieve the pressure sufficiently to keep the mixed material from gushing out of the nozzle 31 when the filled cartridge is removed.

The dasher 40 may be removed from the shaft 35 for cleaning when desired. For this purpose the motor is operated to lift the slide member 28 and then the latch arm 30 is placed under the slide member to hold the closure member 26 elevated against the pressure of the spring 29. The dasher 40 may then be removed from the lower end of the shaft.

Structural Details

The jacket 24 that serves to embrace and reinforce an open-top container 25 is of split construction with separable ends and is provided with a pair of latches 62 to hold the two ends in closed position. The jacket 24 has lugs 64 to receive the thrust of downwardly inclined thumb screws 65 on opposite sides of the jacket, the thumb screws extending through brackets 66. Once a jacketed can is centered in axial alignment with the motor shaft 35 by the introduction of the closure member 26 into the upper open end of the container, the thumb screws 65 may be tightened to immobilize the container and to resist the tendency of the container to be lifted by upward movement of the dasher 40.

The hollow column 22 is reinforced by a brace member 68 that extends diagonally upward from the base 20. The previously mentioned latch arm 30 is mounted on the base 20 by a hinge 70 and a suitable tension spring 72 connects the latch arm with the brace member 68 to urge the latch arm to its release position that is shown in solid lines in FIG. 1.

The motor shaft 35 has a smooth lower end portion 74 which slides through the closure member 26 in a

fluid-tight manner and, as shown in FIG. 1a, has a neck portion 75 at the lower end of the screw thread 36 to receive the previously mentioned split thrust collar 39. The thrust collar 39 is made in two halves which may be reasonably connected by a pair of screws 76. The closure member 26 has an upwardly extending tubular portion 78 which slidably embraces the smooth lower end portion 74 of the shaft 35 for guidance thereby. The tubular portion 78 is internally enlarged as indicated at 80 throughout the major portion of its length to clear the screw thread 36.

The closure member 26 is integrally connected with the slide member 28 by an arm 82 and the slide member is provided with a cross-pin 84 that extends through a pair of diametrically opposite longitudinal slots 85 in the rectangular column 22. Inside the hollow column 22, the cross pin 84 extends through a block 86 at the lower end of an upright rod 88. The upright rod 88 slidably extends through a cap 90 at the upper end of the hollow column 22 to follow the vertical movements of the slide member 28 and the closure member 26. The previously mentioned coil spring 29 that urges the closure member 26 downward surrounds the upright rod 88 in compression between the lower block 86 and the upper cap 90. Thus, the spring 29 continuously urges the closure member 26 downward.

Mounted on the upper end of the upright rod 88 is an angular bracket 92 that carries the upper stop 44 for the reversing switch 42, this upper stop being in form of an adjustable screw with a lock nut 95. Since the upper stop 44 carried by the upright rod 88 is fixed relative to the closure member 26 and since the reversing switch 42 travels with the dasher 40, the upper stop operates the reversing switch to reverse the motor 34 whenever the dasher 40 approaches the closure member. A second lower stop 45 for the reversing switch comprises an adjustable screw provided with a lock nut 98, the screw being threaded into a flange 100 of the previously mentioned bracket arm 54.

The motor 34 together with a switch box 102 and a resistor box 104 for the motor are carried by an upper slide member 105 that slidably embraces the hollow column 22. The switch box 102 carries the previously mentioned master switch 46, the three-position switch 48, the selector switch 50 and the reversing switch 42.

The reversing switch 42 is of the toggle type with an operating arm 106. Slidably mounted in the switch box 102 and extending upward therefrom is an upper operating plunger 108 for the reversing switch 42 which is normally held at an upper limit position by a coil spring 110. This operating plunger is in the path of the upper stop member 44 so that upward movement of the slide member 105 eventually causes retraction of the upper operating plunger by the upper stop member 44 to cause the operating plunger to swing the operating arm 106 of the reversing switch downward to reverse the motor 34. In like manner, a lower operating plunger 112 is slidably mounted in the switch box 102 and extends downward therefrom for contact with the lower stop member 45, the plunger being normally held at its downward limit position by a surrounding coil spring 114.

Certain safety provisions have been found to be desirable to prevent damage to the structure by movement of the motor too far upward during manual operation and by movement downward against the latch member 30 when the latch member is holding the closure member 26 up. Damage by excessive upward movement of the motor 34 is avoided by providing a suitable limit switch to be effective whenever the selector switch 50 is positioned for manual operation. For this purpose, a limit switch 115 may be mounted on the motor 34 for movement against a stop 116 that is fixedly mounted by a bracket 118 on the upper end of the hollow column 22. This limit switch automatically reverses the motor when-

ever the motor is moved too far upward by manipulation of the three-positioned manual switch 48.

Damage that might be caused by forcing the closure 5 26 downward when the latch arm 30 is in its latching position is avoided by employing a latch block 120 on the latch arm 30 to engage the lower edge of the slide member 28. The latch block 120 is secured to the latch arm 30 by suitable frangible means which will break when stressed unduly. For this purpose, the latch block 120 10 may be attached to the latch arm by relatively weak frangible rivets 122. The upper end of the latch arm 30 is bent backwards to an angle as indicated at 124 to make the latch arm ineffective in the absence of the latch block 120. Thus with the latch block 120 removed, the operator cannot employ the latch arm for its purpose 15 without replacing the latch block by a new set of frangible rivets.

As a further safeguard, the latch arm 30 is made short 20 enough in length to hold the closure member 26 at a position too low to permit the container 25 to be positioned under the closure member. With the closure member held elevated against the resistance of the spring 29 by the latch arm 30, the operator finds it necessary to 25 "jog" the three-position manual switch 48 upward to lift the closure to provide clearance for the container 25. The upward movement of the closure member permits the latch arm to be automatically retracted by the spring 72.

Wiring Diagram

FIG. 6 shows a diagram of an electrical control system 30 that may be employed in the described embodiment of the invention. The previously mentioned motor 34 has a pair of field coils 125 by means of which the direction of rotation of the motor may be reversed. The selector switch 50 is a double-throw double-pole switch, the blades of which are connected to the armature of the motor 34. The three-position manual switch 48, the reversing switch 42 and the upper limit switch 115 are also of the double-pole double-throw type. One pair of contacts 126 of the selector switch 50 that are employed for manual operation of the dasher 40 are connected to the switch blades of the three-position switch 48, as shown, and the second pair of contacts 128 of the selector switch 50 that are used for automatic operation are connected to the switch 35 blades of the reversing switch 42.

The pair of contacts 130 of the reversing switch 42 that are used to energize the motor 34 for downward movement of the motor shaft 35 are connected to the two field coils 125 respectively and are connected to the 40 blades of the limit switch 115. The pair of contacts 130 are also connected to the corresponding pair of contacts 132 of the three-position selector switch 48 that are employed for downward movement of the motor shaft. The second pair of contacts 134 of the reversing switch 42 that are employed for upward movement of the motor are connected to the corresponding pair of contacts 135 of the three-position manual switch 48 and the pair of contacts 135 are connected, in turn, to a pair of contacts 136 of the limit switch 115.

The blades of the three-position manual switch 48 are 45 connected to the second pair of contacts 137 of the upper limit switch 115. One of the field coils 125 of the motor is in series with the master switch 46 and with a pair of motor resistors 138 that are housed in the previously mentioned resistor box 104. The purpose of these resistors is to lower the voltage drop across this particular motor to permit the motor to be reversed in the manner described.

The limit switch 115 functions actually as a reversing 50 switch to keep the motor from coasting past the desired limit position. If the three-position manual switch 48 is held in its "up" position after the upper limit switch 115 is operated, the motor will be continually reversed as the upper limit switch and the three-position manual switch alternately exercise control. This alternating ac-

tion, however, will inform the operator that the three-position manual switch 48 should be shifted to its "stop" position.

Operation by an Air Motor

As heretofore stated, in some instances, it is desirable to substitute an air motor for the electric motor 34 since compressed air is commonly available on construction jobs. FIGS. 7 to 9 show diagrammatically how the above described apparatus may be modified by the substitution of an air motor 140 for the electric motor, the air motor functioning to operate a motor shaft 35a which corresponds to the previously mentioned motor shaft 35. The air motor 140 may be connected to a suitable source of compressed air through a conduit 142 which is equipped with a master start and stop valve 144 and which leads to a valve block 145.

As indicated diagrammatically in FIG. 8, the supply conduit 142 is connected to two branch passages 146 and 148 inside the valve block 145 and these two passages are connected to the air motor 140 by corresponding pipes 150 and 152. The flow of pressurized air through the branch passage 146 is controlled by a valve 154 which is a pilot-operated valve having a pilot tube 155. In like manner, flow through the second branch passage 148 is controlled by a similar valve 156 having a pilot tube 158.

An exhaust pipe 160 which is connected with the branch passage 146 between the air motor and the valve 154 is controlled by an exhaust valve 162 having a pilot tube 164. In like manner, an exhaust pipe 165 that is connected to the second branch passage 148 is controlled by an exhaust valve 166 having an associated pilot tube 168.

The manner in which each of the four valves 154, 156, 162 and 166 operate may be understood by reference to the diagrammatic view in FIG. 9 which represents the valve 154 in the branch passage 146. In FIG. 9, a valve body 170 has an inlet passage 172 which terminates at a valve seat 174 in a valve chamber 175. The valve seat is normally closed by a valve member 176 which is unitary with a piston 178 that is slidably mounted in the valve chamber and is provided with an O-ring 180. A suitable coil spring 182 in compression between the piston 178 and the end of the valve chamber at the valve seat 174 exerts pressure on the piston in a direction to unseat the valve member 176. An outlet passage 184 for the actuating air is connected to the valve chamber 175 to receive air from the inlet passage 172 when the valve member 176 is unseated. The pilot tube 155 for the valve 154 is connected to the branch passage 146 on the inlet side of the valve and also communicates with the valve chamber 175 through a bore 185.

If the outer end of the pilot tube 155 is closed, the pressure in the valve chamber 175 above the piston 178 will be the relatively high pressure that exists in the branch pipe 146 on the inlet side of the valve. If the valve member 176 is seated while the outer end of the pilot tube 155 is closed, it will remain seated against the same fluid pressure in the inlet passage 172 because the piston 178 is sufficiently larger than the nose of the valve member 176 to keep the valve member seated in opposition to the opening force exerted by the spring 182. If the outer end of the pilot tube 155 is opened to the atmosphere, however, the pressure drops in the valve chamber 175 above the piston 178 to such an extent that the spring 182 lifts the valve member 176 off its seat to permit air flow through the valve. If the outer end of the pilot tube 155 is suddenly closed while the valve member 176 is unseated as shown in FIG. 9, the pressure in the valve chamber 175 above the piston 178 again rises to the line pressure in the branch pipe 146 and the valve closes. Thus the valve shown in FIG. 9 cuts off flow of compressed air whenever the pilot tube 155 is cut off from the atmosphere and opens whenever the pilot tube is vented to the atmosphere.

The pilot tube 155 of the valve 154 and the pilot tube

168 of the valve 166 are both connected to a control tube 186 so that the two valves open whenever the control tube 186 is vented to the atmosphere and close whenever the control tube 186 is cut off from the atmosphere. In like manner, the pilot tube 158 of the valve 156 and the pilot tube 164 of the valve 162 are connected to a second control tube 188 to open whenever the control tube is vented to the atmosphere.

It is apparent from an inspeciton of FIG. 8 that with the control tube 188 cut off from the atmosphere and the control tube 186 vented to the atmosphere, the valves 154 and 162 will be closed and the valves 156 and 166 will be open. With the valve 154 open, air under pressure is supplied to the air motor 140 through the branch pipe 150 and air from the discharge side of the motor is exhausted through the exhaust valve 166.

On the other hand, with the control tube 186 cut off from the atmosphere and the control tube 188 vented to the atmosphere, the valves 154 and 166 will be closed and the valves 156 and 162 will be open. With the valve 156 open, compressed air is fed to the motor through the pipe 152 and the exhaust from the motor is released to the atmosphere through the valve 162. Thus alternately opening the control tubes 186 and 188 to the atmosphere will cause the air motor 140 to rotate alternately in opposite directions.

The two control tubes 186 and 188 are connected to two normally closed valves 190 and 192 respectively, which two valves together correspond to the three-position manual switch 48 in the previously described control circuit. Thus if the two valves 190 and 192 are closed, the air motor 140 will be idle; if solely the valve 190 is opened, the motor will rotate in a direction to cause the motor shaft 35a to shift upward; and if solely the valve 192 is opened, the air motor will rotate in the reverse direction to cause the shaft 35a to shift downward. These two valves 190 and 192 are preferably of the push button type, both being operated by corresponding plungers.

The control tube 186 is connected by a branch tube 194 to a valve 195 and the control tube 188 is connected by a branch tube 196 to a second valve 198. These two valves 195 and 198 are mechanically interconnected for operation in unison by a selector lever 200. In the position of the selector lever 200 shown in FIG. 7, the two valves 195 and 198 are closed so that control of the air motor 140 resides solely in the two valves 190 and 192. In the alternate position of the selector lever 200, the valve 195 places the branch tube 194 in communication with a control tube 202 that leads to an automatic reversing valve unit that is generally designated by numeral 204. At the same time, the valve 198 places the branch tube 196 in communication with a control tube 205 that also leads to the reversing valve unit.

The reversing valve unit 204 is shown diagrammatically in FIG. 7 as having a control arm 206 by means of which it may be operated in the same manner as a toggle type reversing switch. Thus when the control arm 206 is inclined downward as shown in FIG. 7, the control tube 205 is vented to the atmosphere to cause the air motor 140 to operate in a direction to shift the motor shaft 35a downward. On the other hand, when the control arm 206 is inclined upward, the control tube 202 is open to the atmosphere to cause reverse rotation of the air motor 140.

The automatic reversing valve unit 204 travels up and down with the air motor 140 and the shaft 35a. An upwardly extending rod 210 and a downwardly extending rod 212 also travel with the motor and shaft. The rod 210 is urged upward by a spring 214 and the rod 212 is urged downward by a spring 215 in the manner heretofore described. The upwardly extending rod 214 moves against an upper stop 216 to reverse the air motor when the dasher approaches the closure member and the downwardly extending rod 212 moves against a lower stop 218 to reverse the motor when the dasher approaches the bottom of the mixing container.

The air motor 140 may be stopped or started at any time by means of the master valve 144. With the master valve 144 open to supply compressed air to the valve block 145 and with the selector arm 200 in its rightward position shown in FIG. 7, the motor may be moved upward or downward selectively by manual operation of the two valves 190 and 192. With the selector lever 200 swung to its alternate limit position, the motor will operate and will automatically reverse under control of the automatic reversing valve unit 204. It is apparent that the selector lever 200 corresponds to the selector switch 50 of the previously described electric control.

The reversing valve unit 204 may be of the construction shown in FIG. 10. In FIG. 10, the reversing valve unit comprises a pilot valve 220 having an operating plunger 222, the pilot valve being connected to the control tube 205 and being spring-biased to take an open position. If the operating plunger 222 is not depressed, the valve takes an open position to cause the air motor to operate to shift the shaft in the down direction. In like manner, a second pilot valve 224 having an operating plunger 225 is spring-biased to take an open position and is connected to the control tube 202. If the operating plunger 225 is not depressed the valve causes rotation of the motor for upward movement of the motor shaft.

The previously mentioned control arm 206 of the reversing valve unit 204 is mounted on a pivot 226 and is integral with an upwardly extending operating arm 228 and a downwardly extending operating arm 230. The upwardly extending operating arm 228 is positioned to depress the operating plunger 222 and the lower operating arm 230 is positioned to depress the lower operating plunger 225. The upper operating arm 228 has a latch finger 232 which overhangs a leaf spring 234 that is bent to form a latch shoulder 235. In like manner, the lower operating arm 230 is formed with a latch finger 236 which overhangs a leaf spring 238 that is bent to form a latch shoulder 240.

The previously mentioned upwardly extending operating rod 210 that cooperates with the upper stop 216 is provided with a head 242 at its upper end which is slidably encased by a tube 244. Below the head 242, the tube 244 is swaged to form an inner circumferential rib 245 and a washer 246 that loosely surrounds the rod 210 is urged against this rib by the previously mentioned spring 214. The rod 210 is rigidly connected to the lower rod 212 through a central body 248 and this central body is operatively connected to the control arm 206 by means of a stud 250 which extends through a slightly oversized aperture 252 in the control arm. The lower end of the rod 210 is surrounded by an upwardly extending guide tube 254 that extends upward from the central body 248 and the lower end of the slideable tube 244 telescopes over this guide tube. The previously mentioned spring 214 seats against the upper end of the guide tube 254.

The downwardly extending rod 212 is provided with a head 255 and is enclosed by a second slideable tube 256 with an inner circumferential rib 258. The previously mentioned spring 215 is in compression between a washer 260 and the lower end of a guide tube 262.

The upper leaf spring 234 has an aperture 264 which surrounds the upper guide tube 254 to place the leaf spring in the path of downward movement of the slideable tube 244. In like manner, the lower leaf spring 238 has an aperture 265 to surround the lower guide tube 262 in the path of the upward movement of the slideable tube 256.

With the parts of the reversing valve unit 204 in the positions shown in FIG. 10, the lower pilot valve 224 is free from mechanical pressure to take an open position and thereby open the control tube 202 to the atmosphere. On the other hand, the upper operating arm 228 depresses the operating plunger 222 of the pilot valve 220 to cut off the control tube 205 from the atmosphere. Consequently, the reversing valve unit 204 along with the air motor 140 is traveling upward to cause the upper end of

the upper slideable tube 244 to approach the upper stop 216. Under these conditions, the upper latch finger 232 is in abutment with the upper latch shoulder 235.

When the slideable tube 244 makes contact with the upper stop 216 and the reversing valve unit continues its upward travel, the slideable tube is retracted downward against the opposition of the spring 214 and moves against the leaf spring 234 to flex the leaf spring sufficiently to disengage the latch shoulder 235 from the latch finger 232. At this point, the two operating arms 228 and 230 together with the control arm 206 are free for reversal movement, and the force of the compressed upper spring 214 swings the control arm 206 downward with a snap action.

The downward swing of the control arm 206 rocks the upper operating arm 228 clockwise to release the operating plunger 222 of the upper pilot valve 220 and also rocks the lower operating arm 230 clockwise to depress the operating plunger 225 of the lower pilot valve 224. The lower latch finger 236 is swung past the latch shoulder 240 of the lower leaf spring 238 and then the leaf spring flexes to bring the latching shoulder 240 into position to engage and retain the latch finger 236. Consequently, the control tube 202 is cut off from the atmosphere and the control tube 205 is vented to the atmosphere to cause downward reversal of the air motor 140. When the reversing valve unit 204 approaches the lower stop 218, the reversing valve unit is operated in the opposite respect to reverse the air motor for upward shift of the air motor shaft.

My description in specific detail of the selected practices of the invention will suggest various changes, substitutions and other departures from my disclosure within the spirit and scope of the appended claims.

35 I claim:

1. In an apparatus for mixing ingredients in an open-top container, the combination of: a closure for the open top of the container having a vent for the release of air; yielding means to press said closure downward against the ingredients in the container; an upright support structure; reversible power means movably mounted on said structure for movement longitudinally thereof; a shaft driven by said power means and extending downward therefrom through said closure, said shaft having a screw thread above the closure; a dasher mounted on said shaft inside said container and beneath said closure; and fixed means engaging said screw thread to cause longitudinal movement of the shaft and power means by screw action in response to rotation of the shaft whereby operation of said power means with periodic reversal causes said dasher to reciprocate axially of the container.

2. A combination as set forth in claim 1 in which said dasher is fixedly mounted on said shaft for rotation therewith.

3. A combination as set forth in claim 1 in which said closure has an upwardly extending coaxial tubular portion slidably embracing the shaft to maintain the closure in axial alignment with the container.

4. A combination as set forth in claim 1 which includes latch means to releasably hold said closure up to permit said dasher to be removed from said shaft for cleaning.

5. A combination as set forth in claim 4 in which said latch means is automatically releasable in response to upward movement of the closure away from its latched position; and in which the latch means holds said closure at a height insufficient to clear said container whereby the closure member must be moved upward from its latched position to permit the container to be placed under the closure member.

6. A combination as set forth in claim 4 in which said latch means is frangible to break in the event that said power means is inadvertently operated against the resistance of the latch means.

7. A combination as set forth in claim 1 which in-

11

cludes means to reverse said power means in response to approach of the dasher to said closure and in response to approach of the dasher to the bottom of the container.

8. A combination as set forth in claim 1, which includes means providing a port for dispensing the mixed ingredients from the container; and means to connect said closure to said shaft for axial movement therewith whereby said power means may be employed to cause the closure to force the mixed ingredients out through said port. 10

9. A combination as set forth in claim 8 in which said dispensing port is in said closure.

10. In an apparatus for mixing ingredients in an open-top container, the combination of: a closure for the open top of the container having a vent for the release of air; yielding means to press said closure downward against the ingredients in the container; an upright support structure; reversible power means movably mounted on said structure for movement longitudinally thereof; a shaft driven by said power means and extending downward therefrom through said closure, said shaft having a screw thread above the closure; a dasher mounted on said shaft inside said container and beneath said closure; and fixed means engaging said screw thread to cause longitudinal movement of the shaft and power means by screw action in response to rotation of the shaft; means movable with the power means and operable to reverse the power means; means in the path of movement of said reversing means for contact therewith to reverse the power means when the dasher approaches the bottom of the container; and means in the path of movement of said reversing means for contact therewith to reverse the power means when the dasher approaches the closure. 15

11. A combination as set forth in claim 10 in which said last mentioned contact means is fixed relative to said closure for movement therewith whereby the range of reciprocation of the dasher is determined by the distance between the closure and the bottom of the container.

12. A combination as set forth in claim 11 in which said power means is a motor and said reversing means is a reversing switch having an operating member positioned for contact with said two contact means.

13. A combination as set forth in claim 11 in which said power means is a fluid motor and said reversing means comprises valve means having an operating member positioned for contact with said two contact means.

14. In an apparatus for mixing ingredients in an open-top container, the combination of: a closure for the open top of the container having a vent for the release of air; yielding means to press said closure downward against the ingredients in the container; an upright support structure; reversible power means movably mounted on said structure for movement longitudinally thereof; a shaft driven by said power means and extending downward therefrom through said closure, said shaft having a screw thread above the closure; a dasher mounted on said shaft inside said container and beneath said closure; and fixed means engaging said screw thread to cause longitudinal movement of the shaft and power means by screw action in response to rotation of the shaft; a first means for reversing said power means, said first means being movable with the power means; means in the path of movement of said reversing means for contact therewith to reverse the power means when the dasher approaches the bottom of the container; means in the path of movement of said reversing means for contact therewith to reverse the power means when the dasher approaches the closure; a second manually operable means for controlling the power means; a third means manually operable to connect said power means with said first and second means selectively; means providing a port for dispensing the mixed ingredients from the container; and means to connect said closure with said shaft for axial movement therewith to force the mixed ingredients out through said port. 15

12

15. A combination as set forth in claim 14 in which said power means is an electric motor and said three means are switch means.

16. A combination as set forth in claim 14 in which said power means is a fluid motor and said three means are valve means.

17. A combination as set forth in claim 16 in which said first means comprises: a pair of spring-loaded valves; a rocker member for operation by said two contact means to rock between a first limit position to operate one of the valves of said pair in opposition to its spring resistance and a second limit position to operate the other of the valves of said pair in opposition to its spring resistance.

18. A combination as set forth in claim 16 in which said first means comprises: a pair of spring-loaded valves; a rocker member to rock between a first limit position to operate one of said valves in opposition to its spring resistance and a second limit position to operate the other of said valves in opposition to its spring resistance; means to automatically latch said rocker member in response to movement thereof to its first limit position; means to automatically latch said rocker member in response to movement thereof to its second limit position; and operating means adjacent said rocker member; said operating means being movable in one respect by contact with one of said contact means to unlatch said rocker member at its first limit position and to rock it to its second limit position with consequent latching of the rocker member at its second position and being movable in the opposite respect by contact with the other of said contact means to unlatch said rocker member at its second limit position and to rock it to its first limit position with consequent latching of the rocker member at its first position. 20

19. In an apparatus for mixing ingredients in an open-top container, the combination of: a base structure to support the container; upright support structure mounted on said base structure adjacent the position of the container; a closure to fit slidingly inside the open top of the container; means connected with said closure and slidingly mounted on said upright support structure; spring means in stress between the support structure and said slidingly mounted means to urge said closure downward against the ingredients in the container; motor means mounted on said upright support structure for vertical movement 25

relative thereto; a shaft for rotation by said motor means and extending downward through said closure; a dasher mounted on the lower end of said shaft below said closure for mixing the ingredients in the container, said shaft having a screw threaded portion above the closure; means fixedly mounted on said upright support structure in engagement with said screw thread to cause longitudinal shift of the shaft and motor means by screw action in response to rotation of the shaft by the motor means; and means to reverse the operation of said motor means in response to approach of said dasher to the bottom of the container and in response to approach of the dasher to said closure whereby the dasher is reciprocated to mix the ingredients in the container. 30

20. A combination as set forth in claim 19 which includes: means providing a port in said closure for dispensing the mixed ingredients from said container; means to releasably connect said shaft to said closure with said dasher close to the closure whereby the closure may be moved downward by the shaft to force the mixed ingredients out through said dispensing port; means for manual control of said motor means for the purpose of dispensing the mixed ingredients; and means to make said motor means responsive selectively to either said reversing means or said manual control. 35

21. A reversing valve assembly, comprising: a first valve operable in a first direction and a second direction; a first spring constantly exerting force on said first valve to operate the first valve in the first direction; a second valve operable in a first direction and a second direction; a second spring constantly exerting force on said second 40

45

valve to operate the second valve in its first direction; an operating member to move in one direction to a first limit position to operate said first valve in its second direction in opposition to the first spring and in the opposite direction to a second position to operate said second valve in its second direction in opposition to the second spring; a first latch means to latch said operating member at its first limit position in response to movement of the operating member thereto; a second latch means to latch said operating member at its second limit position in response to movement of the operating member thereto; and a control member movable in one direction to release said first latch means and force said operating member from its first limit position to its second limit position and movable in the opposite direction to release said second latch means and force said operating member from its second limit position to its first limit position.

22. A combination as set forth in claim 21 in which portions of said operating member and portions of said

two latch means are in the path of movement of said control member for contact by the control member.
